UNITED STATES PATENT OFFICE.

MATTHEW MORTON, OF MUSKEGON HEIGHTS, MICHIGAN.

MECHANISM FOR PLANING SHOES AND WEDGES.

No. 901,724.

Specification of Letters Patent.

Patented Oct. 20, 1908.

Application filed December 8, 1906. Serial No. 346,935.

To all whom it may concern:

Be it known that I, MATTHEW MORTON, a citizen of the United States, residing at Muskegon Heights, county of Muskegon, 5 State of Michigan, have invented a certain new and useful Improvement in Mechanism for Planing Shoes and Wedges, of which the following is a specification, reference being had to the accompanying drawings, which 10 form a part of this specification.

My invention has for its object novel mechanism for planing shoes and wedges, the same being more particularly designed for securely holding what are termed shoes 15 and wedges used in the lining of locomotive axle boxes, the wedge being adjustable for taking up the wear. In order to machine these shoes and wedges correctly, it is necessary to have an apparatus which will suit- 20 axle boxes, the wedge being adjustable for up and down from a given point at one end, the adjustability being from a parallel plane to one inch taper to the foot, for example.

My invention consists of the construction, 25 combination and arrangement of devices hereinafter described and claimed and illustrated in the accompanying drawings, in which,

Figure 1 is a view in side elevation. Fig. 30 2 is a view showing features of the holder in plan. Fig. 3 is an end elevation of the holder. Fig. 4 is a view in cross section on the line 4—4, Fig. 1. Fig. 5 is a view in section on the line 5—5, Fig. 1. Fig. 6 is a 35 view of a wedge to be planed.

To accomplish the object of my invention I provide a base plate *a*, the same being applicable to the bed or table of any suitable planing machine indicated at *b*, the same being shown in Fig. 1 herewith provided with 40 a cutter bar *c* and cutting tool *d*. The base plate is provided with a bearing *e* supported within a box receptacle *f* projecting upwardly at the rear end of the base plate, the bearing being supported upon said box receptacle upon pivot pins indicated at *g* and *h*. The base plate is also provided with lugs indicated at *i* and *j* projecting upward at 45 the front thereof, said lugs being machined centrally with the box receptacle. A holder or bar *k* is provided with a journal indicated at *l* upon the rear end thereof, the bearing *e* being formed in the nature of a split ring which is adjustably pivoted on the pins 50 *g*, *h*, the journal of the holder or bar *k* being mounted in said bearing. This bearing is so

constructed as to have a perfect fit in the box receptacle so as to remove all side or lateral strain, and is so arranged that by means of a tension applied with a screw *m* 60 it may be rigidly gripped in position, or by loosening said screw the holder or bar *k* may be turned or rotated as required, the holder or bar fitting between the upwardly projecting lugs *i*, *j*. To this end the forward portion of said holder is preferably rounded on its lateral face as indicated at *n* and *p*. A set screw *q* is provided to raise and lower the front end of the holder the bearing *e* turning upon the pivot pins *g*, the holder being thus 70 oscillatory upon said pivot pins. Bolts or studs *r*, *r* are provided to securely fasten the holder in any position to which it may be oscillated. It will readily be seen that by this mechanism the holder or bar may be 75 revolved upon its axis a portion of a circle, and that its front end may be easily raised or lowered, so as to adjust the holder from the pivotal points *g*, *h*, so as to represent any desired taper or angle, and whereby the 80 wedge to be planed may be made to fit the part to which it is to be applied.

The holder or bar *k* is provided on its upper face with a slot indicated at *s* in which is located a parallel steel bar *t* fitted in said slot so that it may be moved longitudinally of the holder. The holder is also provided with an adjusting screw *u* whereby the steel bar may be moved longitudinally of the holder. The holder is also shown cut away 90 transversely as indicated at *v* and *w*, four jaws indicated by the numerals 7, 8, 9 and 10 being provided to operate in the slots *v*, *w*, said jaws operating at right angles to the bar *t*. The bar *t* is constructed with wedge shaped points indicated at 11 and 12 and said jaws being similarly formed at their inner ends to match the angle of the adjacent points 11 and 12 on the sliding bar, it will readily be seen that by drawing the sliding bar forward by means of the screw *u* that the four jaws will be forced outward thereby centering the work located thereon to be planed, and at the same time the work will be held firmly in place. A wedge to be 100 planed is indicated at 13. A plate or cover 14 protects the sliding bar and sliding jaws and holds them in position.

Attached to the base plate are multiple arms 15 provided with sliding blocks 16 and set screws indicated at 17 to bind against the work. The binding blocks 16 being thus

adjustable to the different widths of shoes or wedges which it may be desired to plane. These binding blocks are preferably constructed so that the outer end is lower than 5 the end coming in contact with the work. The inner ends of the sliding blocks are preferably beveled so as to present a sharp edge against the work. By screwing down on the nuts upon the screws 17 it will be evident that the work is forced down firmly on the top of the underlying holder or bar and at the same time is rigidly held laterally. It will be obvious that by locating the shoe or wedge over the sliding bar and turning 10 the adjusting screw *u*, that the wedge will be bound internally at its sides, and then by fastening down the binding blocks 17 the work is rigidly held upon the top of the holder or bar. The device is also formed 15 with a block 18 so located that the work will strike there against, said block resting against the front side of the bearing *e* on the rear end of the base. An additional support 20 19 is also provided secured to the rear end of 25 the box receptacle *f*, said support having a bearing against the front side or front plate of the shaper or planer, and it can readily be seen that as the ram of the shaper takes 30 its cut on the inward stroke, that the cutting strains are transferred directly against the frame of the machine itself, thereby eliminating vibration and rendering the apparatus much more rigid. The base plate *a* preferably has a tongue and groove engagement 35 upon the table of a shaper or planer so as to be self alining.

This invention is particularly adapted to an ordinary draw cut shaper, but may be used on a planer or other reciprocating 40 machines.

I do not limit myself to the pivoting of the rear end of the holder or bar *e* upon pivot pins *g*, *h*, as for this purpose a ball or socket or other suitable joint might be used 45 if preferred.

What I claim as my invention is:

1. In a mechanism for planing shoes and wedges, a base plate provided with a box receptacle at one end thereof, a bearing journaled in said receptacle, a holder journaled at one end in said bearing whereby the forward end of the holder may be raised and lowered to a desired position of vertical adjustment, and whereby also the holder may be rotated in said bearing to a desired position of lateral adjustment, means at the outer end of the holder to fasten the holder in a desired position of vertical adjustment, means to fasten the holder in a desired position of lateral adjustment, and means to clamp the work upon the holder.

2. In a mechanism for planing shoes and wedges, a base plate provided with a box receptacle at one end thereof, a bearing journaled in said receptacle and held from lateral

movement therein, a holder journaled at one end in said bearing whereby the forward end of the holder may be raised and lowered to a desired position of vertical adjustment and whereby the holder may be rotated in said bearing to a desired position of lateral adjustment, means to secure the holder in a desired position of vertical adjustment, means to interiorly clamp the work upon said holder, and additional means to exteriorly clamp the work upon the holder.

3. In a mechanism for planing shoes and wedges, a base plate provided with a box receptacle at one end thereof, a bearing journaled in said receptacle and held from lateral movement therein, a holder journaled at one end in said bearing whereby the forward end of the holder may be raised and lowered to a desired position of vertical adjustment, and whereby also the holder may be rotated in said bearing to a desired position of lateral adjustment, means to secure the holder in a desired position of vertical adjustment, means to fasten the holder in a desired position of lateral adjustment, a slide movable longitudinally upon the upper surface of the holder, means to exteriorly clamp the work upon the holder, and transversely arranged clamping arms at each side of the holder actuated by said slide to interiorly engage the work.

4. In a mechanism for planing shoes and wedges, a base plate provided with a box receptacle at one end thereof, a bearing journaled in said receptacle and held from lateral movement therein, a holder journaled at one end in said bearing whereby the forward end of the holder may be raised and lowered to a desired position of vertical adjustment, and whereby also the holder may be rotated in said bearing to a desired position of lateral adjustment, means to secure the holder in a desired position of vertical adjustment, means to fasten the holder in a desired position of lateral adjustment, a slide movable longitudinally upon the upper surface of the holder, means to exteriorly clamp the work upon the holder, transversely arranged clamping arms at each side of the holder actuated by said slide to interiorly engage the work, and a cover plate located over said slide and clamping arms.

5. In a mechanism for planing shoes and wedges, a base plate, provided with a box receptacle at one end thereof, a bearing journaled in said receptacle, a vertically oscillatory holder journaled at one end in said bearing, a slide movable longitudinally upon the upper surface of the holder, clamping devices actuated by said slide to interiorly engage the work upon the holder, and additional clamping devices to exteriorly engage the work upon the holder.

6. In a mechanism for planing shoes and wedges, a supporting base, a bearing jour-

naled thereupon, a holder journaled at one end in said bearing whereby the forward end of the holder may be raised and lowered to a desired position of vertical adjustment, and 5 whereby also the holder may be rotated in said bearing to a desired position of lateral adjustment, means at the outer end of the holder to fasten the holder in a desired position of vertical adjustment, means to fasten 10 the holder in a desired position of lateral adjustment, and means to clamp the work upon the holder.

7. In a mechanism for planing shoes and wedges, a base plate, a split ring bearing 15 jointedly engaged upon the rear end of the base plate, a vertically oscillatory and partially rotatable holder extending longitudinally of the base plate journaled in said bearing, means to secure the holder in a given 20 adjusted position in which it may be partially rotated, mechanism at the forward end of the holder and to secure the holder in a given vertically adjusted position, and clamping devices to engage the work upon the 25 holder.

8. In a mechanism for planing shoes and wedges a base plate, a partially rotatable and vertically oscillatory holder jointedly supported at one end thereof upon said plate, 30 means to secure the holder in a given position of adjustment, and lugs at the forward extremities of the holder to engage the holder there between, the lateral surface of said holder being rounded adjacent to said lugs.

9. In a mechanism for planing shoes and wedges a base plate, a partially rotatable and vertically oscillatory holder jointedly supported at one end thereof upon said plate,

means to secure the holder in a given position of adjustment, arms upon each side of 40 the holder provided with sliding blocks and set screws to bind said blocks upon the work.

10. In a mechanism for planing shoes and wedges, a base plate, a partially rotatable and vertically oscillatory holder jointedly 45 supported at one end thereof upon said plate, means to secure the holder in a given position of adjustment, arms upon each side of the holder provided with sliding blocks and set screws to bind said blocks upon the work, 50 the outer ends of said blocks being lower than the inner ends thereof, the inner edges of said blocks being beveled, for the purpose described.

11. In a mechanism for planing shoes and wedges a base plate, a partially rotatable and vertically oscillatory holder jointedly supported at one end thereof upon said plate, means to secure the holder in a given position of adjustment, a horizontally movable slide, said holder constructed with a longitudinal groove upon its upper surface to receive the slide, and with transverse grooves, jaws in said transverse grooves actuated by said slide, said slide constructed 60 with wedge shaped surfaces, and the inner ends of said jaws being beveled to correspond to the wedge shaped surface of the slide.

In testimony whereof, I have signed this 70 specification in the presence of two subscribing witnesses.

MATTHEW MORTON.
